UNITED STATES PATENT OFFICE.

LOUIS H. THULLEN, OF EDGEWOOD PARK, PENNSYLVANIA, ASSIGNOR TO
THE UNION SWITCH AND SIGNAL COMPANY, OF SWISSVALE, PENNSYLVANIA, A CORPORATION OF PENNSYLVANIA.

SIGNALING SYSTEM FOR ALTERNATING CURRENTS.

No. 858,120.

Specification of Letters Patent.

Patented June 25, 1907.

Application filed March 2, 1906. Serial No. 303,773.

To all whom it may concern:

Be it known that I, LOUIS H. THULLEN, of Edgewood Park, Allegheny county, Pennsylvania, have invented a new and useful Signaling System for Alternating Currents, of which the following is a full, clear, and exact description, reference being had to the accompanying drawings, forming part of this specification, in which—

10 Figure 1 is a diagrammatic plan view showing the preferred form of my invention; Figs. 2 and 3 are cross-sections showing different forms of bond which I may employ; and Figs. 4 and 5 are diagrammatic plan views showing other forms of the invention of my broader claims.

My invention relates to block signaling on railroads where alternating current is employed to actuate the signals.

20 The object of the invention is to provide bonds between the successive blocks which will offer high impedance to the alternating current employed for operating the signals while at the same time it will give a free path 25 for the flow of the propulsion current from block to block. The propulsion current may be either direct or alternating, and in either case will be given a free path according to my invention, while the passage of the signal-operating current will be impeded.

In the drawings, referring to the form of Figs. 1, 2 and 3, A, B and C represent the successive blocks of an electric railway.

25 2 is a generator for furnishing propulsion current for the trains or cars, and which may be of the alternating or direct current character.

3 is an alternating current generator which is employed to furnish current to the actuating devices for the signals of the successive blocks.

4 is a transformer which reduces the high potential alternating current traveling the lines 5 and 6, the current being taken to the 45 rails through the wires 7 and 8.

9 represents the signal governing the traffic, and 10 is a relay controlled by the alternating current of the track circuit, and which in turn controls the signal 9.

50 The car is diagrammatically illustrated by the pair of wheels 11, 12 illustrating the trolley connection to the trolley wire or third rail 13.

The system above described is old and well-known. The feature of my invention 55 lies in the bond employed at opposite ends of the successive blocks. Each bond consists of two metals, one of which is magnetic, and the other non-magnetic.

In the form of Fig. 2, 14 is a copper core 60 around which are placed laminated iron disks 15.

In the form of Fig. 3 I show a bond having a copper core 16 which is surrounded by a series of iron or steel wires 17 which extend 65 longitudinally.

It will be understood that the magnetic and non-magnetic portions of the bond may be combined in many different ways; for example, the iron may constitute the core with 70 the copper on the outside, or they may be arranged side by side without departing from the spirit of my invention, since I consider myself the first to use a bond which is built up from magnetic and non-magnetic material arranged to give a low ohmic resistance to the propulsion current which would travel 75 through the copper or non-magnetic metal, while at the same time giving a high impedance to the alternating current due to the 80 close proximity of the magnetic material. By laminating the magnetic portion of the bond the propulsion current is prevented 85 from reducing the impedance to the alternating block signal current. If the magnetic material were not laminated, the propulsion current would act to reduce the impedance of the bond. As before stated, the propulsion current may be either direct or alternating, 90 and in either case will be given a free path.

In order to still further increase the impedance of the bond, I preferably increase its length over what it would be if arranged at right angles to the rails. This increase in length may be carried out by extending the 95 bond through any irregular path between the rails.

The bonds are connected at their intermediate parts by the connecting wires 18, through which the propulsion current flows 100 from one section to the next.

In order to still further increase the impedance of the bond I may extend it in such form that the current through a leg close to a rail flows in the same direction as through 105 such adjacent rail.

In Figs. 4 and 5, I show a peculiar placing of the bond for this purpose. In Fig. 4 the current for the block signal system enters from the transformer 19 at the intermediate 5 or central parts of the rails of each block, through the wires 20 and 21. The bonds 22 are arranged in the form of closed loops with the legs crossing each other and connected to the rails, one rail being shown as continuous 10 while the other is in sections. The legs of the loops are closely adjacent to the rails, and the current through any one leg parallel to a rail flows in the same direction as the current through the adjacent rail. On account of 15 these currents flowing in the same direction, the impedance through the bond is increased. In Fig. 5 I show the bonds 23 and 24 arranged in two different forms at the opposite ends of the same block. In this form the 20 current enters the end of the block through the transformer 25 and consequently the bond 23 is in the form of a parallelogram or loop open at one end, while at the other end of the block the bond 24 is of closed parallelogram form with one leg passing beneath the other. The arrows on the rails 26 and 27 show the alternating current for the block 25 signal as flowing in opposite directions at the same instant; and owing to the peculiar arrangement of the bonds the current will flow 30 through any leg parallel and adjacent to one of the rails in the same direction as through such rail. By this peculiar placing of the bond as a whole relative to the rails, I increase 35 the impedance to the alternating current through the bonds. While the bonds in this form, as in the first form, may be made of the combined magnetic and non-magnetic material, they may also be made of magnetic 40 material or non-magnetic material alone when used in this form. For example, they may be formed of iron or steel rails, or bars, as magnetic material has more impedance to alternating current than non-magnetic material, while with the copper bars the peculiar 45 placing increases the impedance to the alternating current while giving low ohmic resistance to the propulsion current. In this form of Figs. 4 and 5, it will be noted that one rail 50 is continuous while the other is broken into block sections; while in the first form both rails are sub-divided. In this form, therefore, the current flows through the continuous rail from block to block. These details, 55 however, are unimportant so far as regards my invention.

The advantages of my invention result from increasing the impedance to the alternating signal current between the blocks, 60 while still giving low resistance to the passage of the propulsion current, in a simple and effective way. Where the loop arrangement of the second form is employed to increase the impedance of the alternating signal current, the conductor may be of any de-

sired character; and on the other hand, where the improved bond of combined magnetic and non-magnetic materials is employed, it may be used either with or without giving it the shape and placing of the second form. 70

Many variations may be made in the form and arrangement of the bond, its shape and placing; the propulsion current may be either direct or alternating, and the manner and place of feeding in the block-actuating current may be varied. As to the form, in which the impedance is increased by the placing of the bond, the bond may have one limb extending parallel to another limb, in which both limbs are carrying a current in 80 the same direction. In this case the limbs of the bond itself would act upon each other to increase the impedance.

Many other variations may be made without departing from my invention. 85

Such novel features of the signaling system as are herein shown and described, but not claimed, form the subject-matter of other pending applications; viz., Serial Nos. 192,145, and 192,146, filed February 5th, 90 1904, and No. 282,702, filed October 14th, 1905.

I claim:—

1. A bond for electric roads containing magnetic and non-magnetic materials extending side by side longitudinally of the track; substantially as described. 95

2. A bond for electric roads containing magnetic and non-magnetic material side by side longitudinally of the track, the magnetic material being laminated; substantially as described. 100

3. A bond for electric roads arranged to connect adjacent sections and formed of copper and iron, or steel, extending side by side in electrical contact with each other; substantially as described. 105

4. In an electric railroad, a bond for connecting adjacent sections or blocks, said bond being formed of copper and iron, or steel, the iron or steel inclosing the copper and being laminated; substantially as described. 110

5. A bond having a non-magnetic core and a covering of magnetic laminated material; substantially as described. 115

6. In electric roads having a block signal system arranged for alternating currents, a bond arranged to connect adjacent sections of track and having portions extending adjacent to the rails and arranged to carry a current parallel with that passing through the adjacent rails; substantially as described. 120

7. In an electric road having a block signaling system arranged for alternating current, a bond having a limb extending alongside and adjacent to a conductor having a current flowing in the same direction as through the said limb or bond; substantially as described. 125

8. In electric roads having an alternating 130

- current block system, a bond having a limb extending alongside and adjacent to a rail, and connections for passing a current in the same direction through said limb and through the rail; substantially as described.
9. In electric roads, a bond arranged to connect adjacent sections of the track rails and having a limb in inductive relation to the rail; substantially as described.
10. In an electric road, a bond for connecting adjacent sections or blocks, said bond having a copper conductor, and iron, or steel, the iron or steel being in inductive relation to the copper; substantially as described.
11. An inductive bond for connecting adjacent track sections comprising a non-magnetic material and a laminated magnetic material and inclosing the non-magnetic material.
12. In an automatic block signal system, a closed track circuit, and an induction bond the conductors of which are composed of copper and magnetic material in inductive relation to each other; substantially as described.
13. A bond for electric roads, arranged to connect adjacent sections of track, and formed of copper and magnetic material, both the copper and the magnetic material forming a path for the signaling current between the rails of the same track section; substantially as described.
14. In an electric railroad, in which both rails are used for the return of the propulsion current, a closed track circuit, and a bond arranged to connect adjacent sections of the track and composed of copper and magnetic

material in electric contact with each other and forming an impedance for the track current; substantially as described.

15. In electric roads having a block-signaling system with an alternating current closed track circuit, an inductive bond arranged to connect adjacent track sections and having portions which extend adjacent to the track rails, and which are so arranged as to increase the impedance in the bond by reason of the presence of the current in the rails; substantially as described.

16. In an automatic block signal system, a closed track circuit, and an inductive bond, the conductor of which is composed of copper, and thin plates of magnetic material surrounding the copper conductor and placed transversely thereto; substantially as described.

17. In an automatic block signaling system, a closed track circuit, and inductive bonds, the conductors of which are composed of copper, and magnetic material arranged to increase the self-induction of the copper; substantially as described.

18. An inductive bond, having a continuous conductor, one of whose limbs is arranged in inductive relation to another limb of the same conductor; substantially as described.

In testimony whereof, I have hereunto set my hand.

LOUIS H. THULLEN.
